UNITED STATES PATENT OFFICE.

JOHN CRANSTON, OF TRENTON, AND WILLIAM D. LE BAR, OF WYANDOTTE, MICHIGAN.

ELECTROLYTIC CELL.

1,398,784.

Specification of Letters Patent.

Patented Nov. 29, 1921.

Application filed October 19, 1920. Serial No. 418,003.

To all whom it may concern:

Be it known that we, JOHN CRANSTON, a citizen of Canada, and a resident of Trenton, in the county of Wayne and State of Michigan, and WILLIAM D. LE BAR, a citizen of the United States, and a resident of Wyandotte, in the county of Wayne and State of Michigan, have invented a new and Improved Electrolytic Cell, of which the following is a full, clear, and exact description.

This invention relates to electrolytic cells, and has particular reference to one adapted for the production of chlorin and alkaline liquor.

An object of the invention is the provision of a cell which is simple, compact and efficient and is capable of ready assembly and disassembly.

Another object resides in the provision of means whereby the anode structure can be adjusted relative to the other parts of the device so that the functioning of the anodes can be considerably prolonged.

A further object resides in the provision of means whereby the chlorin, the alkaline liquor, and the hydrogen gas evolved during the operation of the cell can be very readily collected.

A still further object resides in the particular construction and arrangement of parts hereinafter described and claimed and shown in the accompanying drawings.

In general the invention comprises an electrolytic cell having a body portion of some impervious material in which are suspended a plurality of anodes immersed in a suitable electrolyte. A portion of each side of the body portion is cut away, and against

this cut-away portion a suitable diaphragm is placed, this diaphragm being backed by the metallic sheet serving as the cathode. The cathode at its lower end is provided with an integral portion thereof forming a

trough or other suitable receptacle for the collection of the alkaline liquor formed. The sides of the upper portion of the body of the cell are dependent far enough into the electrolyte to form a partition or ceiling wall between the anode and cathode chambers, whereby the gas formed in the anode chamber is separated.

The top of the body portion is provided with a plurality of slots through which the several anodes are introduced. The anodes are mounted in sets, forming a plurality of

metallic plates which are readily attached to the top of the body portion and are connected thereto in a gas-tight manner. The removal of these plates with the sets of anodes thereon permits the faces of the anodes to be adjusted and reversed relative to the faces of the cathodes, so that when an anode has become eaten away by the electrolytic action to such an extent as to impair its efficiency, it may be readily removed from the cell and turned around to present a new and undefective face to the cathode.

A further feature of the invention comprises a sheet of metal or other suitable substance which depends from the top of the body portion into the trough or receptacle at the bottom of the cathode structure to provide a sealed chamber in which hydrogen may be collected and from which the hydrogen may be drawn off at will.

Other features of our invention will be apparent from a consideration of the description and claims shown in connection with the accompanying drawings.

The invention is illustrated in the drawings, of which—

Figure 1 is a side elevation;

Fig. 2 is a plan view;

Fig. 3 is a sectional view taken on the line 3—3 of Fig. 1; and

Fig. 4 is a detail of the cathode structure.

As shown in the drawings, the invention comprises a cell body portion 1 in the form of a rectangular block of impervious material, such as slate, concrete or stone. This block along its top face is provided with two longitudinally extending, spaced slot portions 2 and 3. The depth of these slots extends down to the lower portion of the body 1, and at this place the side walls of the block are cut away. The side walls 4 and 5 of the block extend downwardly to a point which is designed to be below the level of a suitable electrolyte or fluid 6. The slots 2 and 3 are separated from each other by an integral partition or wall 7. By reason of the extension of side walls 4 and 5 into the liquid electrolyte 6 and the provision of the intervening wall 7, it will be noticed that above the electrolyte a pair of chambers is provided. Into these chambers anodes 8 are adapted to extend, the lower ends of the anodes being immersed in the liquid electrolyte to a proper depth.

A plurality of these anodes 8 are disposed in each of the chambers formed by the

slotted portions 2 and 3 and are, in sets, connected in any suitable fashion to metallic plates 9 and 10 which extend along the top of the slotted portions 2 and 3 and engage the face of the block 1 adjacent the openings of these slotted portions and are suitably fastened to the block portion by any suitable means, such as screws 11 and 12. The lower faces of these metallic plates may be provided with some sort of paint or enamel or other coating, which is adapted to protect the metallic lower surfaces of the plates from the action of acid or gas formed within the chamber of the cell.

15 It will be observed that since the anodes are connected in sets to the metallic plates above mentioned, these sets may be readily removed with the plates from the cell. The reason for this ready removal will be apparent from a consideration of the hereinafter described operation of the machine.

20 The upper portion of the block 1 is provided with outwardly extending flange portions 13 and 14, and disposed along the sides of the block 1, particularly adjacent the cut-away portions mentioned above, are asbestos diaphragms 15 which are backed by metallic plates 16 serving as cathodes. These metallic plates 16 are preferably provided 25 with a number of slots or perforations 17, as clearly shown in Fig. 4, particularly in that part of the cathode 16 adjacent the cut-away portions of the block 1. To the cathode 16 is connected a suitable terminal bar 30 18 which may extend upwardly through a suitable aperture in the flange portions 13 and 14 and may be suitably sealed therein in any desired manner. The upper end of the terminal bar 18 may be connected to 35 40 suitable electrical circuit wires.

45 Particularly in Fig. 3 it will be noted that the lower end of the cathode 16 is turned up, as shown at 19, to form a trough, the ends of which, such as 20, are turned in and provided to close the ends of the trough. It will be also noted that the cut-away portions of the block 1 are now closed by the disposition thereagainst of the diaphragm 15 and the cathode 16. This provides that the 50 inner portion of the block 1 forms a chamber containing the electrolyte 6 and the anodes 8, in which chamber the electrolytic action takes place.

55 Suitably fastened to the outside of the flange portions 13 and 14 and along its edges to the body portion of the block 1, on each side thereof, is a metallic plate 21 at the lower end of which is adapted to extend down into the trough 19 and form a 60 seal with any liquor which may be collected therein. Between this plate 21, the cathode 16 and the body portion of the block 1 there is, therefore, formed a chamber 22, so that any gas generated above the 65 surface of the liquor in the trough 19 can be

collected in this chamber and can be led off in any suitable manner. It will be observed that the diaphragm 15, the cathode 16 and the plate 21, along their edges, are provided with a plurality of apertures which, when 70 these parts are in their proper position, are alined with each other; and through these alined apertures fastening devices, such as bolts 22', extend, and through the body portion of the block 1, to fasten the various 75 parts to the block 1 in a simple and efficient manner.

It will also be observed from Figs. 1 and 2 that a passage 23 is provided from one end of the upper portion of the interior chamber of the cell, whereby any gas formed therein may be led off. The upper end of the block portion, at the opposite end from the passage 23, is furthermore, provided with a passage 24 leading to the inner chamber above the normal level of the electrolyte, so that more electrolyte can be added thereto at will.

In the operation of the device, assuming the anodes, which are preferably made of 90 graphite, are in place in sets attached to their metallic supporting plates and these plates are suitably fastened to the top face of the block 1. The electrolyte having been placed within the inner chamber at the 95 proper level, an electric current now being passed from the source of power, through the anode, the electrolyte and the cathode, causes an electrolytic action. The solution generally used as an electrolyte is a brine 100 solution, for example, a saturated solution of sodium chlorid. The passage of electric current through this electrolyte results in the formation of chlorin gas above the level of the electrolyte within the inner chamber, 105 and the generation of sodium hydroxid or an alkaline liquor as the electrolyte permeates through the diaphragm 15 and comes in contact with the cathode 16. This caustic liquor passes through the cells or apertures 110 17 of the cathode 16 and down the outer face thereof into the trough 19, where it is collected. A suitable pipe, such as 25, may be connected to an end of the trough 19 to lead off the alkaline liquor, as desired. 115

Hydrogen generated in the process may tend to separate out from the alkaline liquor in the trough 19, and for this reason the end of the plate 21 dips into the liquor to form a sealed chamber above the level of 120 the liquor, in which the hydrogen can be collected. This gas may then be passed off by any suitable pipe connection (not shown).

When the electrolyte becomes reduced in the degree of its concentration, more electrolyte may be introduced through the passage 24 above mentioned. It will be noticed that a substantial portion of electrolytic action takes place between the cathode 21 and one face of each of the anodes which lies 130

adjacent thereto. In time this electrolytic process will result in this face of the anode being eaten away whereby the path of the electric current is increased, thereby increasing 5 the resistance of the path and resulting in the necessity for the application of a larger potential to the cell. To eliminate the necessity for this increase of voltage to the cell, we have provided the above-men- 10 tioned anode structure. Therefore, when the outer faces of the sets of anodes adjacent the cathode surfaces become defective, for the reason above mentioned, we loosen the connection between the plates 9 and 10 and 15 the upper portion of the block 1 and remove the plates 9 and 10 with the sets of anodes thereon from the cell. By turning these plates around, with their sets of anodes thereon, we are able to present to the cathode 20 surfaces in this new position fresh, un- affected faces of the anodes which previously had been disposed away from the cathode surfaces. By this simple arrangement of parts we can use a plurality of anodes over 25 a longer period of time in the operation of the cell than heretofore has been possible.

Our structure, furthermore, provides a simple, gas-tight chamber between the anode and cathode structures in which the chlorid 30 gas generated may be collected. Furthermore, our invention is advantageous in that a simple stamped sheet metal cathode not only acts as this electrode but at its lower end is formed into a trough portion to collect the alkaline liquor formed during the 35 process.

What we claim is:

1. An electrode comprising a metallic plate, and a trough turned up on the lower 40 end of the plate from the metal of the plate and adapted to receive liquid.

2. An electrode comprising a metallic plate, and a trough on the lower end of the plate, said trough adapted to receive liquid.

45 3. An electrode comprising a metallic plate, and a trough turned up on the lower end of the plate and adapted to receive liquid.

4. An electrolytic cell comprising a body 50 portion having a liquid chamber and openings in the walls thereof, a plate electrode disposed against said openings and having perforations therein through which the liquid is adapted to pass, and a trough at the bottom of the electrode adapted to receive liquid.

5. An electrolytic cell comprising a body 55 portion having a liquid chamber and openings in the walls thereof, a plate electrode disposed against said openings and having perforations therein through which the liquid is adapted to pass, and a trough turned up on the lower end of the electrode and adapted to receive the liquid.

65 6. An electrolytic cell comprising a body

portion having a liquid chamber and openings in the walls thereof, a plate electrode disposed against said openings and having perforations therein through which the liquid is adapted to pass, and a trough turned 70 up on the lower end of the electrode from the metal of the electrode and adapted to receive the liquid.

7. An electrolytic cell comprising a body portion having a liquid chamber and openings in the walls thereof, a plate electrode disposed against said openings and having perforations therein through which the liquid is adapted to pass, a trough at the bottom of the electrode and adapted to receive 75 the liquid, and a plate spaced from the electrode to form a chamber therein, the lower end of said plate adapted to dip into the liquid in the trough, said plate being fastened along its other edges to the body portion to make the chamber gas tight.

8. An electrolytic cell comprising a body portion having a liquid chamber and openings in the walls thereof, flanges on the upper lateral edges of the body portion, a plate 90 electrode disposed against said openings and having perforations therein through which the liquid is adapted to pass, a trough at the bottom of the plate electrode adapted to receive the liquid, and a second plate spaced 95 from the electrode and having its lower edge dipping into the trough, said second plate being fastened to the flanges and to the body portions along its other edges to form a gas-tight chamber between itself and the 100 plate electrode.

9. An electrolytic cell comprising a body portion having an electrolyte chamber within the body portion, portions of the top face of the body portion being cut away to provide passages extending into the electrolyte chamber, a plate adapted to be fastened to the top face of the body portion to close the cut-away portions, and an electrode supported on said plate and extending into the electrolyte chamber.

10. An electrolytic cell comprising a body portion of impervious material, the top and side faces of said body portion being cut away to provide openings therein leading to 115 the electrolyte chamber, a plurality of electrodes extending into the electrolyte chamber, a plate supporting said electrodes and forming a closure for the openings in the top face of the body portion, and means for detachably fastening said plate to the body portion.

11. An electrolytic cell comprising a body portion of impervious material, the top and side faces of said body portion being cut 125 away to provide openings therein leading to the electrolyte chamber, a plurality of electrodes extending into the electrolyte chamber, a plate supporting said electrodes and forming a closure for the openings in the top 130 face of the body portion.

- face of the body portion, means for detachably fastening said plate to the body portion, and a second electrode disposed against the openings in the side wall of the body portion and spaced apart from the first electrode and the body of the electrolyte within the body portion adapted to form a current path between the electrodes.
12. An electrolytic cell comprising a body portion of impervious material and having an electrolyte chamber within and a slot in the upper face of the body portion connecting with the electrolyte chamber, a metallic plate adapted to close the slot, and a plurality of electrodes supported from said plate.
13. An electrolytic cell comprising a body portion having an electrolyte chamber therein and a passage cut in the top face of the body portion leading to the electrolyte chamber, a partition wall extending between the end walls of the body portion and separating the passage into two narrow slotlike portions, a plurality of electrodes disposed within these slotted portions and cooperating with the electrolyte, a plate supporting the electrodes in each of said slotted portions, and means for detachably fastening the plates to the body portion whereby the slotted portions are closed, said plates being adapted to be removed with the electrodes from the wall and replaced thereon in reverse position to reverse the relation of the electrodes with respect to the walls of the body portion.
14. An electrolytic cell comprising a body portion of impervious material having an electrolyte chamber therein and an opening in the top face of the body portion leading to the electrolyte chamber, a plurality of electrodes disposed through said openings and into the electrolyte chamber, and means for supporting said electrodes in sets and adapted to close the opening when in place, said means being detachably fastened to the body portion and removable at will therefrom with the electrode, so that the relation of the electrode to the side walls of the body portion may be reversed.
15. An electrolytic cell comprising a body portion having an electrolyte chamber therein and openings in the top and side portions of the body portion leading to the electrolyte chamber, an electrode disposed in one of said openings and extending into the electrolyte, a second electrode disposed against another of said openings with an edge thereof spaced apart and adjacent an edge of the first-mentioned electrode, means for supporting the first-mentioned electrode and closing the openings in the body portion through which it extends, and means for removably fastening said supporting means to the body portion whereby the supporting means and the first-mentioned electrode can be removed from the body portion and inserted therein in reverse position so that the relation of the first-mentioned electrode and the second electrode can be reversed at will.

JOHN CRANSTON.

WILLIAM D. LE BAR.
